UNITED STATES PATENT OFFICE.

MEYER DAVIS, OF CHICAGO, ILLINOIS.

DESIGN FOR A PHONOGRAPH-CABINET.

54,982.

Specification for Design.

Patented Apr. 27, 1920.

Application filed January 9, 1920. Serial No. 350,459. Term of patent 14 years.

To all whom it may concern:

Be it known that I, MEYER DAVIS, a citizen of the United States, residing at Chicago, in the county of Cook and State of Illinois, have invented a new, original, and ornamental Design for Phonograph-Cabinets, of which the following is a specification, reference being had to the accompanying drawings, forming part thereof.

As shown in this drawing, Figure 1 is a front view of a phonograph cabinet showing my new design; and Fig. 2 is a plan view of the same.

It will be seen from these drawings that this phonograph or talking machine cabinet is of substantially triangular form and the lower portion for holding the records closely follows the outline of the upper or main portion of the cabinet.

I claim:

The ornamental design for a phonograph cabinet as shown.

MEYER DAVIS.
